EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

SHUTTLE FOR WEFT-REPLENISHING LOOMS.

1,074,662.

Specification of Letters Patent.

Patented Oct. 7, 1913.

Application filed April 5, 1913. Serial No. 759,039.

To all whom it may concern:

Be it known that I, EDWARD S. STIMPSON, of Hopedale, in the county of Worcester and State of Massachusetts, have invented certain new and useful Improvements in Shuttles for Weft-Replenishing Looms, of which the following is a specification.

The present invention relates to a spreader employed to maintain in proper relative position the holding jaws of the shuttle spring which is employed in automatically threading shuttles for the purpose of yieldingly grasping the head of the bobbin or other weft carrier.

15 The improvement is illustrated in the accompanying drawings in which—

Figure 1 is a plan view of the weft carrier holding end of a shuttle. Fig. 2 is a longitudinal vertical section of the same end 20 of the shuttle. Fig. 3 is a perspective view of the spreader detached.

The improved spreader is intended to keep in proper position the two jaws of the bobbin holding shuttle spring when the jaws 25 are bent from a single piece of sheet metal; and it is particularly intended for use with such a shuttle spring when the jaws are of reduced width at their holding ends as compared with the width of their connected shanks. Such a shuttle spring having jaws of reduced width is illustrated in the accompanying drawings wherein A is the shuttle, B is the shuttle spring and C is a bobbin held between the jaws *a*, of the shuttle 30 spring. As shown in Fig. 2 of the drawings the free ends *a* of the jaws are of less width than the shanks *b*. Both jaws are made of a single piece of metal bent into shape, as illustrated in Fig. 1 and the uniting bend 35 between the two jaws is shown in section at *c* in Fig. 2. The shuttle spring B is retained within the shuttle by means of a transverse bolt D passing through apertures in the shanks *b* of the two jaws.

40 Coöoperating with the shuttle spring B is an inclined sheet metal shuttle spring guard E. This guard E has an integral horizontal top plate *d* having an aperture through

which passes a screw F which secures the guard to the body of the shuttle. Also, the 50 guard E has an integral bottom plate *e* resting upon the bottom wall of the shuttle as shown in Fig. 2. The shuttle spring shanks *b* fit between the two plates *d*, *e*, of the guard E. The bottom plate *e* of the 55 guard has transverse wings *f* (see Fig. 1) which extend beneath the bowed portions of the jaws *a* close to the base of the bobbin C. Consequently the plate *e* supports the shuttle spring underneath against the strain 60 resulting from the insertion of a fresh bobbin and the expulsion of a spent one. The reaction is withstood by the top plate *d* of the guard E. This guard also has the usual incline at front to direct the incoming weft- 65 carrier to the spring jaws.

As thus far described, there is nothing which is not disclosed in prior patents or applications. The specifically illustrated shuttle spring is set forth in application for 70 Letters Patent of the United States filed by me September 12, 1912, Serial No. 719,956. The specifically illustrated guard E is shown in that application and also in United States Letters Patent to Janelle No. 782,505, February 14, 1905, and in United States Letters Patent of McCaslin No. 1,017,782, February 20, 1912.

The present improvement resides in the spreader G and its relation to the shuttle 80 spring B, the bolt D, and the guard E. The spreader G is made of a single piece of sheet metal bent into shape. It has a top leg *g* and a bottom leg *i* connected together by an inclined bridge *h*. The top and bottom legs 85 *g* and *i* are parallel to each other, and are of uniform width with the inclined bridge *h* and just sufficiently wide to fit tightly between the shanks *b* of the two jaws. Accordingly the jaws are maintained the 90 proper distance apart and can not be bent too closely together when screwing up the bolt D into place, this otherwise being apt to occur by reason of the yielding of the wooden walls of the shuttle. The spreader 95 G has an upwardly rising tongue *j* at the

rear end of the bottom leg *i* which extends closely and snugly between the retaining bolt *D* and the connecting bend *c* of the two jaws. Accordingly, the spreader is 5 maintained accurately in place. The free end of the top leg *g* of the spreader has two lateral oppositely projecting arms, *h*, each of which extends outwardly beyond the top plate *d* of the guard *E* and above the top of 10 the corresponding jaw, this being rendered possible because of the downward inclination of this portion of the jaw between the shank and the narrow holding end of the jaw. Each arm *h* extends outwardly sufficiently far to extend within the corresponding recess *m* of the shuttle wall, this recess being provided in the usual manner to accommodate the outward spread of the jaws when the bobbin is inserted. Each arm *h* 20 has a reversely turned wing *l* on its outer side fitting closely against the face of the shuttle wall recess *m*. By reason of this construction of the spreader, it not only prevents the jaws of the shuttle spring from 25 being forced toward each other, thus avoiding the possibility of the jaws being so close together as not to receive the butt of the weft carrier; but, in addition, the spreader effectually locks the shuttle spring in place 30 and prevents any movement thereof either up or down or sidewise. The arm *h* of the spreader fits snugly between the upper edges of the jaws and the top plate *d* of the guard thereby preventing any upward movement 35 of the jaws which might occur through the looseness of fit between the top and bottom plates of the guard.

I claim—

1. A loom shuttle having, in combination, 40 a one piece weft-carrier holding shuttle-spring bent from a single piece of metal and having two jaws, the shanks of which are wider than the weft-carrier holding ends; a guard having integral top and bottom plates which embrace said shanks between them, said top plate being fastened to the shuttle; a transverse bolt in the shuttle passing through the shanks of both jaws; a recess in each side wall of the shuttle 45 opposite the holding end of each jaw; and a one piece spreader having parallel top and bottom legs and an inclined bridge connecting them, the bottom leg having an upwardly projecting tongue, and the top leg having laterally projecting arms each with a reversely turned wing, said legs and bridge fitting between the jaw shanks, said bridge being forward of said bolt, said tongue fitting between said bolt and the connecting 50 bend of the two jaws, each of said arms extending between the guard and a reduced portion of one of the jaws, and each of said wings entering one of the shuttle recesses and lying close to its face.

65 2. A loom shuttle having, in combination,

a one piece weft-carrier holding shuttle-spring bent from a single piece of metal and having two jaws; a guard having top and bottom plates which embrace said shanks between them, said top plate being 70 fastened to the shuttle; a transverse bolt in the shuttle passing through the shanks of both jaws; and a spreader having top and bottom legs and a bridge connecting them, the bottom leg having an upwardly projecting tongue, and the top leg having laterally projecting arms, said legs and bridge fitting between the jaw shanks, said bridge being forward of said bolt, said tongue fitting between said bolt and the connecting 75 bend of the two jaws, and each of said arms extending between the guard and one of the jaws.

3. A loom shuttle having, in combination, 80 a one piece weft-carrier holding shuttle-spring bent from a single piece of metal and having two jaws; a guard having top and bottom plates which embrace said shanks between them; a transverse bolt in the shuttle passing through the shanks of both jaws; and a spreader having top and bottom legs and a bridge connecting them, the bottom leg having an upwardly projecting tongue, and the top leg having laterally projecting arms, said legs and bridge fitting between the jaw shanks, said bridge being forward of said bolt, said tongue fitting between said bolt and the connecting 85 bend of the two jaws, and each of said arms extending between the guard and one of the jaws.

4. A loom shuttle having, in combination, 90 a one piece weft-carrier holding shuttle-spring bent from a single piece of metal and having two jaws, the shanks of which are wider than the weft-carrier holding ends; a guard having top and bottom plates which embrace said shanks between them; and a spreader having laterally projecting arms, said spreader fitting between the jaw shanks, and each of said arms extending between the guard and a reduced portion 95 of one of the jaws.

5. A loom shuttle having, in combination, 100 a one piece weft-carrier holding shuttle-spring bent from a single piece of metal and having two jaws; a transverse bolt in the shuttle passing through the shanks of both jaws; and a spreader having top and bottom legs and an inclined bridge connecting them, the bottom leg having an upwardly projecting tongue, said legs and bridge fitting between the jaw shanks, said bridge being forward of said bolt, and said tongue fitting between said bolt and the 110 connecting bend of the two jaws.

6. A loom shuttle having, in combination, 115 a one piece weft-carrier holding shuttle-spring bent from a single piece of metal and having two jaws; a transverse bolt in 120

125

the shuttle passing through the shanks of both jaws; and a spreader fitting between the jaw shanks and having an upwardly extending tongue fitting snugly between said 5 bolt and the connecting bend of the two jaws.

In witness whereof, I have hereunto

signed my name in the presence of two subscribing witnesses.
